HEEL SECUREMENT

Andrew J. Book, Buena Vista, Ohio, and Jean
Price Johnson, Maysville, Ky.

Application February 18, 1935, Serial No. 7,098

3 Claims. (Cl. 36—42)

This invention relates to means for securing heels to shoes and has for its object to provide a construction simple in parts, more efficient in use, and less costly to apply, than those heretofore proposed.

With these and other objects in view the invention resides in the novel details of construction and combinations of parts more fully described hereinafter and particularly pointed out in the claims.

Referring to the accompanying drawing forming a part of this specification and in which like numerals designate like parts in all the views—

Fig. 1 is a vertical sectional view through the heel of a shoe illustrating the application of this invention; and

Fig. 2 is an enlarged sectional view illustrating a modification of some of the parts shown in Fig. 1.

In order that this invention may be better understood it is said that heretofore there has been experienced considerable difficulty, particularly in the case of ladies' shoes and slippers, in keeping the heel firmly secured to the shoe or slipper because of the relative great height of the heel, causing considerable leverage strain to be placed upon the joint between the heel and the sole. Mechanical means for securing a heel to the sole have been proposed, but such devices have been so constructed as to seriously interfere with the steps of assembling the shoe at the factory, or else have made necessary a substantial undoing of work already finished, thereby adding considerably to the cost of production. Therefore, the principal object of this present invention is the provision of a mechanical securing means which does not interfere with any of the manufacturing steps and procedure now used in shoe factories, thereby keeping the cost down to a minimum, while another important object is the adaptability of the principle of this securing means to heels of varying height.

In the drawing the upper portions of a shoe have been omitted for clearness, the sole portion 45 of the shoe as shown comprising the insole 1 and the outsole 2. This sole combination is provided with an opening 3 extending completely therethrough just above where the heel 4 is located, said opening being of circular or other 50 shape as desired, and over this opening is positioned a metallic plate 5 whose central portion has been punched to provide the countersink 6 extending into said opening. An important feature of this invention is that the boss 7, 55 created by punching said plate or otherwise form-

ing the countersink 6, extends from the plane of the main body portion of said plate a distance which is no greater than a fraction of the thickness of the sole; i. e. the boss 7 will not protrude through the opening 3.

The heel 4 is provided with a bore 10 of a diameter to receive the relatively long screw 11, said bore having an enlarged portion 12 at the bottom of the heel to receive therein a lock washer 13 of lead or other suitable metal preferably countersunk to fittingly receive the head 14 of said screw, the bore 12 being sufficiently deep to completely contain said washer and said screw head thus permitting the top lift 15 to be applied and secured, as by the nail 16, in flush association with 15 the surface of said heel.

The bore 10 has a second portion 20 of enlarged diameter in the upper portion of the heel for receiving therein a short connector or sleeve member 21 internally threaded throughout for 20 receiving the end of the screw 11, there being provided a definite shoulder 22 where the bores 10 and 20 meet. Thus it will be seen that, upon actuation of the screw 11, the sleeve may be drawn to seat firmly upon said shoulder.

A relatively short screw 25 is provided to be threaded into the upper portion of said sleeve, the head of said screw being suitably formed to have a slight rocking engagement with the countersunk portion of the plate 5, the depth of 30 the latter being sufficient to completely contain the screw head. A thin fiber or leather sheet 26 is provided to cover the plate 5.

From the foregoing description it will thus be apparent that, during the manufacture of the 35 shoe, the plate 5 together with the short screw 25 may be placed in the insole in the insole cutting room and retained temporarily in position by the protective cover sheet 26. After said plate and screw are inserted the insole is nailed to 40 last and goes through the lasting machine, sole laying, levelling, welt machine, trimming machine, and then to the heelng department of the factory, the screw 25 being so short that it will 45 not protrude through the combined sole structure a sufficient distance to interfere with these shoe treating and/or assembling operations.

The wood heeler then connects the sleeve 21 to the short screw 25, applies glue over the top 50 of and into the large bore 20 of the heel, and then places the heel on the heel seat forcing said sleeve into said bore. The outer surface of said sleeve is preferably roughened or provided with indentations 27 into which the glue will key, 55

thereby preventing any possibility of the heel turning after the glue has hardened.

The shoe is then placed in a suitable machine by which necessary pressure is applied to make the heel and heel seat inseparably glued, then the lock washer 13 is inserted in the enlarged bore 12 at the bottom of the heel and the long screw 11 inserted through this washer and threaded into the sleeve while the pressure is still retained. In this operation the screw 11 is turned to bring the sleeve tightly against the shoulder 22, and then the short screw 25 is turned tightly into the opposite end of said sleeve, the protective cover 26 having been previously lifted or moved out of the way to permit actuation of the short screw. After this operation the shoe is then removed from the pressure machine since the heel is permanently fastened thereto, the protective cover 26 is permanently secured over the plate, and the shoe is then sent for attachment of the top lift 15 after which the shoe is ready for the packing room.

Both screws are preferably pointed to facilitate positive entry into the ends of the connector or sleeve 21, and the short screw 25 has a relatively floating, loose, or universal fit in the countersink of the plate 5 to permit the heel to slide the heel in any direction to obtain a perfect fit upon the sole. The lock washer prevents the screw 11 from loosening and also takes the strain off of the wood heel while said screw is being tightened. In no case is the length of the sleeve 21 sufficient to extend from the shoulder 22 to the edge of the boss 7 created by the counter-sinking of plate 5, thereby insuring a gap or space to permit the fullest possible and necessary pressure to be applied through the screws 11 and 25 for securing the heel to the shoe.

The yieldable fit of the head of the screw 25 in the countersink 6 permits adjustment of the entire screw assembly in accordance with the angle formed between the axis of the bore 10 and the plane of the plate 5. Further, this principle of securement is applicable to heels of different height, the only change necessary being in the length of the longer screw employed, the sleeve 21 being of sufficient length to permit small variations in the over-all length of the screw assembly.

By making the lock washer of non-rusting soft metal, a substantially moisture-proof seat is provided for the head of the larger screw 11, thus insulating the wood fibers of the heel from disastrous rust erosion and maintaining the strength of the fibers where pressure of the screwhead is desired retained. This is considered important since the joint between the top lift 15 and the heel 4 is but a small fraction of an inch above the ground surface and therefore very apt to pass moisture to the bore 12 and said screwhead. If desired all of the above described metallic members could be of non-rustable or rust-resisting metal having the necessary strength to withstand and/or support the pressures applied.

It is obvious that those skilled in the art may vary the details of construction and arrangements of parts without departing from the spirit of the invention, and therefore it is desired not to be limited to the foregoing disclosure except as may be required by the claims.

What is claimed is:

1. A heel and sole securement for ladies' shoes the same comprising a pair of tensioning members, one for disposal within the confines of the sole to permit working operations upon the sole during manufacture of the shoe, an element for connecting said members and holding them together under proper securing tension, and a bearing plate for the sole confining member, said plate adapted to be supported by the inner surface of the sole and having a recessed portion to accommodate the head of said sole confining member in positions adjustably in accordance with the inclination of the heel to the sole. 20

2. In a shoe the combination of a sole provided in the heel engaging portion with an opening extending therethrough; a plate disposed over said opening and having a countersunk portion extending into said opening; a heel provided with a bore extending from top to bottom thereof in substantial registry with the opening of said sole; a threaded member having a bearing in the lower portion of said heel and extending upwardly in said bore; a headed second threaded member, the head thereof held by the countersunk portion of said plate, the shank of said member having a diameter less than the diameter of the opening in the sole to permit adjustability in the seating of said member on said plate in accordance with the inclination of the heel to the sole, said member of a length to lie substantially within the confines of said sole; and a connector joining said threaded members.

3. In a shoe the combination of a sole provided in the heel engaging portion with an opening extending therethrough; a plate disposed over said opening and having a countersunk portion extending into said opening; a heel provided with a bore extending from top to bottom thereof, the opposite ends of said bore being enlarged, said bore in substantial registry with the opening of said sole; a threaded member having a bearing in the lower bore enlargement and extending into said bore; a headed second threaded member, the head thereof held by the countersunk portion of said plate, the shank of said member having a diameter less than the diameter of the opening in the sole to permit adjustability in the seating of said member on said plate in accordance with the inclination of the heel to the sole, said member of a length to lie substantially within the confines of said sole; and a connector joining said threaded members and secured to the surface of and disposed in the upper bore enlargement. 60
